UNITED STATES PATENT OFFICE.

WILLIAM H. WETMORE, OF GREENSBORO, NORTH CAROLINA.

INKSTAND.

SPECIFICATION forming part of Letters Patent No. 767,856, dated August 16, 1904.

Application filed March 21, 1904. Serial No. 199,218. (No model.)

To all whom it may concern:

Be it known that I, WILLIAM H. WETMORE, a citizen of the United States, residing at Greensboro, in the county of Guilford and 5 State of North Carolina, have invented new and useful Improvements in Inkstands, of which the following is a specification.

This invention relates more particularly to a cup to be used in connection with the bottle 10 in which ink is sold in such manner that the ink can be supplied to the cup from said bottle as from a reservoir; but within the limits of the invention a reservoir other than the bottle in which the ink is sold can be used.

15 The reservoir may be open; but a closed reservoir is more particularly employed. The cup holds the ink into which the pen is dipped.

In accordance with the invention the inkstand is composed of a reservoir and a communicating cup, connected with each other 20 through the medium of a neck or a substitute therefor, such as a hole or socket, on the reservoir, and is provided with a device in the nature of a valve, which opens and closes the

25 communication between reservoir and cup, according to the position thereof, without requiring the cup and reservoir to be disconnected for the purpose. Most advantageously the reservoir has in its neck a vent (in other

30 words, an air-inlet opening) distinct from the discharge-opening, through which it supplies the cup, and this vent is opened and closed at the same time as said discharge-opening.

35 By opening the valve the ink will run from the reservoir into the cup if the reservoir and cup are placed in proper relative positions, and when a proper supply has been received in the cup the closing of the valve retains ink in the reservoir. By using a bottle

40 or other form of closed reservoir no evaporation can then take place from the ink in the reservoir. Moreover, the cup and reservoir can be so arranged that the ink can be returned to the reservoir by inverting the res-

45 ervoir and cup and adjusting the valve to open the communication between them. The valve might be formed in various ways within the limits of the invention, since I believe I am the first to devise an inkstand in general of the 50 preceding description with or without a vent

distinct from the discharge-opening; but it is an advantage and further improvement to have the valve united to the cup and movable therewith relatively to said reservoir, so that to adjust the valve the cup is turned or otherwise appropriately shifted. The cup then takes the place of a wheel or handle for manipulating the valve. By having the two united the construction is simplified, and by utilizing the cup as the manipulating device 60 for the valve the liability of soiling one's fingers in shifting the valve is lessened. So far as I am aware it is new, broadly, to combine a reservoir with a communicating cup and a valve united to said cup and movable therewith relatively to said reservoir for opening and closing communication between the reservoir and cup, and such combination is therefore included in the invention without reference to the manner of connecting the 70 reservoir and cup, although an additional claim is made to the same when the cup and reservoir are connected by a neck or its substitute on the reservoir.

For securing the cup to the reservoir a 75 plug-and-socket connection is advantageously employed, the rotation or other movement of one part of such connection relatively to the other being utilized to shift the valve for opening and closing the communication between the reservoir and cup, and it is considered more advantageous that the socket part of the connection should be in the form of a movable sleeve, screw-threaded or otherwise 80 suitably formed, the plug part being immovable on the reservoir so far as the operation of the valve is concerned. This more advantageous arrangement is secured in one form of the invention by having a sleeve which is united to both the valve and the cup and is 85 movable with both to fit over an outwardly-projecting neck on the reservoir, while in another form said sleeve fits over the outer end of a perforated stopper whose inner end constitutes a plug in the bore of such neck. 90

95 So far as I am aware I am the first to combine either a cup or a cup and a valve with a reservoir by the aid of a sleeve, which is united to such cup or such valve, or with both, and is movable therewith relatively to said reser- 100

voir, and such general combinations, all and singular, are included in the invention as well as a cup or a cup and valve having an attaching-sleeve united to and movable with the cup 5 or valve, or with both.

The cup may be made in various forms; but it is an advantage and special improvement to make it annular.

Further improvements consist (a) in providing the cup with a lid pendent in the mouth of the cup, which lid can readily be pushed aside to insert the pen, and (b) in providing a division-plate inside the cup on the back wall of the same to confine the ink when (the cup 15 being attached to a reservoir) the reservoir is turned up to return the ink into the same from the cup.

The cup can be attached to the neck of the reservoir (or to a substitute for said neck) 20 with or without having a closure for the opening through the said neck; but it is considered more advantageous to have such closure, and a still further improvement in this regard consists in making the closure integral—that 25 is, in one piece—with the neck. In such case the discharge-opening can be made large, so as to serve as a filling as well as a discharge opening, or an additional filling-opening can be provided.

30 A bottle or reservoir provided with a neck and also with an integrally-formed closure perforated with a discharge-opening and a vent is believed to be broadly new and is so claimed.

35 A bottle or reservoir provided with a neck or its substitute and an additional filling-opening formed in a second neck or otherwise constituted forms part of the invention where said neck or its substitute is provided with a 40 closure (integrally formed or otherwise constituted) perforated with a discharge-opening and a vent.

The invention also comprises the additional parts, improvements, and combinations hereinafter set forth.

45 In the accompanying drawings, which form part of this specification, different forms of inkstand are illustrated, each of which is in accordance with the invention or parts thereof. 50 Modifications, additions, and omissions can be made so long as the substance of any one or more of the hereinafter-written claims is taken.

Figure 1 is a front view, and Fig. 2 a vertical longitudinal section, of an inkstand with 55 double-necked reservoir. Fig. 3 is a partial view, in vertical longitudinal section, of an inkstand whose reservoir has a single screw-threaded neck; and Figs. 4, 5, 6, 7, 8, 9, 10, and 60 11 are views in vertical longitudinal section of other forms, Fig. 10 being a complete view in such section and the other figures partial views.

In Figs. 2, 3, 4, 5, and 9 the valve is shown 65 in position to close the communication be-

tween the reservoir and cup, while in Figs. 6, 7, 8, and 11 it is shown in the open position. In Fig. 10 a self-feeding arrangement is illustrated with the valve closed.

In practice ink is commonly sold either in 70 bottles with plain neck closed by a solid cork or else in bottles with externally-threaded neck closed by a screw-cap or else, thirdly, in bottles with plain neck closed by a perforated stopper provided with an externally-screw-threaded portion and a screw-cap over the end. The cup of the present invention can be adapted to any of these forms, the cap or cork being removed, or it can be adapted to other forms of bottle. 75

80 Referring to Figs. 1 and 2, the reservoir *a* is provided with two necks *b* and *c*. The neck *b* is screw-threaded externally and would be closed by a screw-cap if the reservoir *a* should be used as a shipping vessel. When the ink 85 is to be used, the cap would be taken off. The neck *c* is a plain neck and surrounds a filling-opening which is closed with the solid cork *d* when the reservoir has been filled. For refilling the cork *d* can be withdrawn and 90 replaced. The ink is discharged through the neck *b*.

95 The cup *e* is connected with the reservoir through the neck *b* and communicates with said reservoir through a discharge-opening in 100 said neck. As shown, there is a plug-and-socket connection between the cup and reservoir, the sleeve *f*, which is united to cup, forming the socket part of the connection, while the neck *b* forms the plug part. The 105 two engage by their screw-threads. The sleeve *f* thus forms a rotatory attaching device. To prevent ink from leaking out between the sleeve and neck, a packing-ring *g*—say of soft rubber or other suitable material—110 may be interposed between the end of the sleeve and the body of the reservoir at the base of the neck *b*.

115 The cup *e* is provided with a valve for opening and closing the communication between the reservoir and cup, which valve, as shown, is movable with both the cup *e* and its rotatory attaching device *f* and is constituted by the disk *h*. At the edges of the disk there are 120 holes *j*, best in the form of slits, and when the cup *e*, with its sleeve *f* and valve-disk *h*, is screwed out these holes are brought beyond the end of the neck *b*, so that ink can flow out of one hole *j* while air enters by the other.

125 Behind the valve-disk *h* is a packing-disk *k*, whose periphery is held in a groove. When the cup, with its sleeve and valve-disk, are screwed in, the packing-disk *k* is pressed against the mouth of the neck *b*, completely closing the same.

130 As shown, there is in the mouth of the neck *b* an integrally-formed closure *l*, perforated with a vent (or air-inlet) *m* and a discharge-opening *n*.

At *p* is a low partition or division-plate. 135

When the reservoir is turned to bring the cup on top, the plate *p* confines the ink in the pockets *q*.

In the mouth of the cup a plate *r* is hung 5 by rings *s*. It closes the cup, (so as to lessen evaporation;) but it can easily be pushed in to allow a pen to be dipped into the ink in the cup *e*.

The cup *e* is annular, forming a peripheral 10 rim, which is interiorly concave. The annular form is considered advantageous for each of two reasons: First, it furnishes a peripheral rim for turning the sleeve *f* in screwing the same onto and off of the neck *b*, as 15 well as in turning it to open and close the valve, and, second, it furnishes a receptacle for the ink in almost all positions of the reservoir and cup.

As shown, the neck *b* is eccentrically placed; 20 but it is not necessary that it should be so arranged. In Figs. 4, 5, 6, 7, 8, 9, and 11 a concentrically-placed neck is shown.

The reservoir *a* might be of any shape, but 25 is shown as square in cross-section. When placed on one of its sides, it is not liable to roll. It does not need a stand to restrain it. With an annular cup the reservoir (whether square or cylindrical) could rest on any one 30 of its sides, (the plate *r* being properly hung or dispensed with.) If made to rest on what is, as shown, the top of the reservoir, the opening *m* would become the discharge-opening and the opening *n* the vent.

If the ink is shipped in the reservoir *a*, 35 one would remove the cap from the neck *b* and screw the sleeve *f* over said neck, the reservoir being held in an upright position. Then placing the reservoir on its side, as shown in Figs. 1 and 2, and adjusting the disk *h* so 40 as to bring the holes *j* beyond the end of the neck, ink will flow out of the reservoir into the cup. When the desired quantity of ink has been received in the cup *e*, this latter, with its sleeve *f*, is so turned that the disk *h* 45 presses the packing *k* against the end of the neck *b* and arrests the outflow. The pen is dipped into cup *e* through the opening in the front of the cup, the pendent plate *r* (if used) being pushed aside.

50 When the ink in the cup needs replenishing, the valve is moved to reestablish the communication between the reservoir and cup, and, if necessary, the reservoir is tilted to make the ink flow into the neck *b*.

55 Instead of laying the reservoir on its side it could be placed on end after supplying the cup *e* with ink and closing the valve *h*.

To return the ink to the bottle or reservoir *a*, the latter is turned upright before opening 60 the valve. The cup and sleeve should be turned sufficiently to bring the lowermost edges of the holes *j* beyond the end of the neck *b*, so that all the ink will flow out of the cup *e*. During the operation of returning the ink 65 the plate *p* would aid in confining the same to

the space about the opening *n*, so that air from the bottle or reservoir *a* might freely escape through the vent *m*. When the ink has been returned, rotation of the cup *e* closes the openings *m* *n* and prevents evaporation of 70 the ink in the reservoir *a*. The ink could of course be returned without the aid of the division-plate *p*, and, if preferred, such division-plate could be dispensed with, as could also the pendent plate *r* and the closure *l*; but 75 the use of each and all of them is considered advantageous. In Fig. 9 an inkstand is shown without division-plate, pendent plate, or closure in the reservoir-neck.

In Fig. 3 the pendent plate *r* is not shown; 80 neither is there any separate filling-opening, such as furnished by neck *c* of Figs. 1 and 2. The discharge-opening *n* is made large, so as 85 the better to serve for filling purposes. The cup *e* is annular, but without the peripheral indentations of Figs. 1 and 2. Its shape is also modified otherwise. Instead of having a packing-ring between the end of the sleeve and the body of the reservoir, as shown at *g* in Fig. 2, there is a packing-ring *x* set in a 90 groove in the sleeve *f* and surrounding a cylindrical portion of the neck, which it hugs closely, so as to prevent the passage of ink. In other respects the inkstand of Fig. 3 is the same as that of Figs. 1 and 2, and its parts 95 are similarly lettered.

In Fig. 4 the tapered end *a* of an ordinary cylindrical bottle is shown. The plain centrally-placed neck *t* is closed by the stopper *v*, perforated by the discharge-opening *n* and 100 vent *m*. The outer portion *w* of the stopper is screw-threaded. The stopper is taken out in order to fill the bottle. It is then replaced, and a cap is screwed onto the portion *w* in order to close the passages *m* and *n* for shipment. To use this bottle as the reservoir of 105 an inkstand, the cap is removed from the portion *w* of the stopper and the sleeve *f* of the cup *e* is screwed on instead. The valve *h* *j* is the same as in Figs. 1, 2, and 3. Instead 110 of having a packing *g* between the end of the sleeve *f* and an opposing shoulder the cup of Fig. 4 has a packing-ring *x* in a groove in the sleeve *f*, and this ring *x* slides over a cylindrical portion *y*, which it hugs closely. It 115 will be understood that any form of packing can be used in any form of inkstand to which it can be adapted.

In Fig. 5 the bottle or reservoir *a* has a single screw-threaded neck *b* centrally disposed. The division-plate *p* is not exhibited, and the cup *e* is differently shaped; but the sleeve *f*, disk *h*, holes *j*, packing *k*, and packing *g* are as in Figs. 1, 2, and 3. The neck *b* instead of having an integrally-formed closure has a closure in the form of an inserted stopper *z*—say of soft rubber—with longitudinal grooves 2 and 3 in its periphery, said grooves constituting the vent and the discharge-openings respectively. 130

In Fig. 6 the cup *e* is no longer annular, and there is a hole 4 through the disk *h* in place of one of the holes *j* at its periphery. The packing-disk *k* is supposed to be cemented 5 onto the surface of the disk *h*. In other respects the construction is the same as that of Fig. 5. In Fig. 6 the valve is shown open, in which position the hole 4 registers with the vent-groove 2 in the stopper *z*.

In Fig. 7 the plug part 5 of the plug-and-socket connection is on the cup *e* (being formed integrally therewith) and the socket part is formed by interiorly threading the neck 6. At the base of the neck 6 is a closure 7, formed 15 integral with the reservoir and perforated by a vent 8 and a discharge-opening 9. The plug 5 is perforated with passages 10 and 11, which in the open position of the valve register with the vent 8 and discharge-opening 9, respectively. At 12 is a packing-disk cemented on 20 the end of the plug. When the plug 5 is screwed home, the disk 12 is pressed over the openings 8 and 9 to close the same.

The cup *e* in Fig. 7 is not annular; but it 25 has a pocket 13 and a peripheral rim formed partly by said pocket and partly by the continuation 14 of its walls.

In Fig. 8 the sleeve *f* of the cup *e* is screwed over the neck *b* on the reservoir *a*. This neck 30 has a separately-formed closure consisting of a stopper 15, (say of soft rubber,) perforated with passages 16 and 17, which serve as the vent and the discharge-opening, respectively. The outer end of the stopper is shown as provided 35 with a flange 18, which overlaps the end of the neck *b* and fits closely against the inner surface of the sleeve *f*, (which is here cylindrical,) so as to constitute a packing to prevent ink from passing between the sleeve *f* and neck *b*. The disk *h* has holes 4 and 19, 40 which are in line with the vent 16 and discharge-opening 17, respectively, when, as shown, the cup *e* and sleeve *f* are turned to open the communication between the reservoir 45 *a* and cup *e*. When the sleeve *f* is screwed home, the disk *h* bears on the end of the stopper 15 and effectively closes the passages 16 and 17, the holes 4 and 19 being no longer in line therewith.

In Fig. 9 the inkstand shown is like that of Fig. 5 only the stopper 7 is dispensed with, so that there is no distinction of vent and discharge-opening, the bore of the neck being fully open. The disk *h* in pressing the packing *k* against the end of the neck *b* effectively 55 closes its bore.

In Fig. 10 the reservoir *a* is double-necked, as in Figs. 1 and 2; but the integrally-formed closure *l* of the neck *b* is perforated with an 60 opening 20, which serves both as discharge-opening and vent. The cup *e*, which is shown as annular, has only one hole, *j*. The lower part of its front wall is above this hole, which is the sole means of allowing air to enter and 65 ink to leave the reservoir. Ink, therefore, may

fill the lower part of the cup to the level of the hole *j*, whereupon the flow of ink is arrested until the level of the ink in the cup falls and allows air to enter the reservoir by said hole *j* and opening 20. The inkstand is thus 70 self-feeding. In like manner any of the inkstands shown can be made self-feeding.

It will be observed that inkstand of Fig. 10 would be identical with that of Fig. 2 if one should close the opening *n* and corresponding 75 hole *j*, should dispense with the pendent plate *r*, and should appropriately modify the shape of the cup *e* of Figs. 1 and 9. No modification of the cup would be essential, however, to a self-feeding inkstand, because, as shown 80 in Fig. 2, the front wall of the cup *e* extends inward beyond the holes *j*, and if the reservoir of Fig. 2 should be placed in the position of Fig. 10 said front wall would extend above the hole *j*, which corresponds with opening *m*, 85 and the ink could not overflow, provided there was no way for the air to enter the reservoir except through said hole *j*.

In Fig. 10 the front wall of the cup *e* is extended not only above the hole *j*, but also above 90 the opening 20. The ink in the cup *e* would consequently seal the opening 20, even if the disks *h* and *k* should be dispensed with. Dispensing with such disks (without proper substitutes) would do away with the valve for 95 closing and opening the communication between the reservoir *a* and cup *e*; but while such valve is most useful and an essential element in many of the hereinafter-written claims it is not essential to all of them.

In Fig. 11 the sleeve 21 is lined with packing 22 and turns on the smooth exterior of a neck 23, which is closed by a stopper 15 (say of soft rubber) perforated with passages 16 and 17 for the vent and discharge-opening, 105 respectively. The disk *h* has therein two holes 4 and 19, which are brought into line with the passages 16 and 17, respectively, when it is desired to open the communication between the reservoir *a* and cup *e*, as shown. The disk 110 *h* may bear at all times against the end of the stopper 15, which would best project beyond the neck 23, as shown, the turning of the disk merely moving the holes 4 and 19 out of line with the corresponding passages 16 and 17. 115

The expression in the hereinafter-written claims of "features" or "devices" (in the plural) is intended to include one or more such features or devices, and the expression of a "feature" or "device" (in the singular) is intended 120 to include one such feature or device at the least and not necessarily to exclude the use of more than one, if appropriate.

I claim as my invention or discovery—

1. An inkstand composed of a reservoir, and 125 a communicating-cup, connected with each other through a neck on the reservoir, and provided with a valve which opens and closes communication between the reservoir and cup according to the said valve's position, said cup 130

being adapted to allow a pen to be dipped readily into the ink therein and to retain ink when the reservoir is horizontal, substantially as described.

- 5 2. An inkstand composed of a reservoir, and a communicating-cup, connected with each other through a neck on the reservoir, and provided with a valve which opens and closes communication between the reservoir and cup 10 according to the said valve's position, and also with a vent in said neck in addition to the discharge-opening therein, which vent and discharge-opening are closed and unclosed simultaneously, said cup being adapted to allow a 15 pen to be dipped readily into the ink therein and to retain ink when the reservoir is horizontal, substantially as described.

3. A cup which is adapted to allow a pen to be dipped readily into ink therein, provided 20 with a valve, and also with means for connecting said cup and valve to a reservoir through a neck on said reservoir, said cup having an upright wall on the side opposite the valve-controlled orifice, substantially as described.

- 25 4. An inkstand composed of a reservoir, and a communicating-cup, and provided with a valve united to said cup and movable therewith relatively to said reservoir to open and close communication between the reservoir 30 and cup, said cup being adapted to allow a pen to be dipped readily into the ink therein and to retain ink when the reservoir is horizontal, substantially as described.

5. A cup which is adapted to allow a pen 35 to be dipped readily into the ink therein, provided with a valve united thereto, and also with means for connecting said cup with a reservoir, said cup having an upright wall on the side opposite the valve-controlled orifice, 40 substantially as described.

6. An inkstand composed of a reservoir, and a communicating-cup connected with said reservoir by a plug-and-socket connection and provided with a valve which is shifted by the 45 movement of one part of said connection relatively to the other in order to open and close the communication between the reservoir and cup, said cup being adapted to allow a pen to be dipped readily into the ink therein and to 50 retain ink when the reservoir is horizontal, substantially as described.

7. A cup which is adapted to allow a pen to be dipped readily into the ink therein, provided with a valve, and also with a rotatory attaching device, the valve movable with said device, said cup having an upright wall on the side opposite the valve-controlled orifice, substantially as described.

8. A cup which is adapted to allow a pen 60 to be dipped readily into the ink therein, provided with a valve, and also with a rotatory attaching device, the valve movable with said cup, said cup having an upright wall on the side opposite the valve-controlled orifice, substantially as described.

9. A cup which is adapted to allow a pen to be dipped readily into the ink therein, provided with a valve, and also with a rotatory attaching device, the cup and valve and device being all movable together, said cup having 70 an upright wall on the side opposite the valve-controlled orifice, substantially as described.

10. A cup which is adapted to allow a pen to be dipped readily into the ink therein, provided with an attaching device in the form of 75 a sleeve, the depth of said cup being transverse to the axis of said sleeve, substantially as described.

11. An inkstand composed of a reservoir provided with a neck, and a cup which is 80 adapted to allow a pen to be dipped readily into the ink therein, provided with an attaching device in the form of a sleeve, the depth of said cup being transverse to the axis of said sleeve, substantially as described. 85

12. A cup which is adapted to allow a pen to be dipped readily into the ink therein, provided with a peripherical rim and a rotatory attaching device, the depth of said cup being transverse to the axis of rotation, substan- 90 tially as described.

13. An inkstand composed of a reservoir provided with a neck, and a cup which is 95 adapted to allow a pen to be dipped readily into the ink therein, provided with a peripherical rim and a rotatory attaching device, the depth of said cup being transverse to the axis of rotation, substantially as described.

14. An inkstand composed of a reservoir, and a communicating-cup of annular form, 100 said cup being adapted to allow a pen to be dipped readily into the ink therein, substan- tially as described.

15. An inkstand composed of a reservoir, a communicating-cup of annular form, and a 105 valve for opening and closing the communication between the reservoir and cup, said cup being adapted to allow a pen to be dipped readily into the ink therein, substantially as described. 110

16. An inkstand composed of a reservoir, and a communicating-cup provided with a lid, pendent in the mouth of said cup, substantially as described.

17. An inkstand composed of a reservoir, 115 and a communicating-cup which is adapted to allow a pen to be dipped readily into the ink therein, provided with a division-plate inside the cup on the back wall of the same, substantially as described. 120

18. An inkstand composed of a reservoir provided with a neck and also with a perforated closure for the opening through said neck, and a communicating-cup connected with the reservoir through said neck, said cup 125 being adapted to allow a pen to be dipped readily into the ink therein and to retain ink when the reservoir is horizontal, substantially as described.

19. An inkstand composed of a reservoir 130

- provided with a neck and also with a perforated closure for the opening through said neck, said closure being formed integral with said neck, and a communicating-cup connected 5 with the reservoir through said neck, said cup being adapted to allow a pen to be dipped readily into the ink therein and to retain ink when the reservoir is horizontal, substantially as described.
- 10 20. A reservoir having a neck, and also an integrally-formed closure located within said neck and provided with a discharge-opening and a vent which are both wholly located at the neck end of the reservoir, substantially 15 as described.
21. A reservoir having a neck and an additional filling-opening and also a closure located within said neck and provided with a discharge-opening and a vent which are both 20 wholly located at the neck end of the reservoir, substantially as described.
22. A reservoir having a neck and an additional filling-opening and also an integrally-formed closure located within said neck and 25 provided with a discharge-opening and a vent which are both wholly located at the neck end of the reservoir, substantially as described.
23. A reservoir provided with each of the three following features, namely: first, a neck, 30 second, an additional filling-opening, third, a closure for said neck having therein a discharge-opening and a vent, in combination with a cup connected with said reservoir through said neck, substantially as described.
- 35 24. A cup, having a flat valve-disk, and also an attaching device in the form of a screw-threaded sleeve, both disk and sleeve being united to said cup and movable therewith, the depth of said cup being transverse to the axis 40 of said sleeve, substantially as described.
25. An annular cup, having a flat valve-disk at the back of said cup, and also an attaching device in the form of a screw-threaded sleeve, both disk and sleeve being united to said cup 45 and movable therewith, substantially as described.
26. A cup which is adapted to allow a pen to be dipped readily into the ink therein, provided with an attaching device, a peripherical 50 rim, and pockets, substantially as described.
27. A cup having two orifices in the back wall thereof and a division-plate on said wall inside the cup between said orifices, said cup being provided with means for attaching the 55 same to a reservoir, substantially as described.
28. A cup having two holes in the back wall thereof and rotatory means for attaching the said cup to a reservoir, the depth of the cup being transverse to the axis of rotation, substantially as described. 60
29. An inkstand composed of a reservoir having a neck and a vent and discharge-opening in a closure in said neck, a valved cup having in the back wall thereof holes which correspond with said vent and discharge-opening, 65 respectively, and a rotatory plug-and-socket connection between said reservoir and cup, the depth of the cup being transverse to the axis of rotation, substantially as described.
30. A cup having a sleeve and a valve-disk 70 and a valve-controlled hole beyond the inner periphery of said sleeve, substantially as described.
31. An inkstand composed of a reservoir provided with a neck, and a cup having a sleeve, 75 which engages said neck, and also having a valve-disk and a valve-controlled hole beyond the portion of said disk which closes the neck, substantially as described.
32. An inkstand composed of a reservoir 80 provided with a neck having a closure therein with a vent and a discharge-opening in said closure, a peripherically-rimmed cup provided with a valve-disk which covers both the vent and the discharge-opening and also with valve-controlled holes corresponding with said vent and discharge-opening, respectively, and a rotatory plug-and-socket connection between said reservoir and cup, the depth of the cup 85 being transverse to the axis of rotation, substantially as described. 90
33. The combination with a necked reservoir having a vent and a discharge-opening in a closure in said neck, of a cup movable relatively to said reservoir and said closure and 95 provided with a valve-disk which covers said vent as well as said discharge-opening and also with valve-controlled holes corresponding with said vent and said discharge-opening, respectively, substantially as described. 100
34. The combination with a reservoir provided with a neck, of a rotatory cup having a valve-disk of greater diameter than said neck and a valve-controlled hole beyond the portion of said disk which closes said neck, substantially as described. 105
